UNITED STATES PATENT OFFICE.

CARL WEIDMANN, OF GREVENBERG, GERMANY.

COMBUSTION-ENGINE.

No. 837,989.

Specification of Letters Patent.

Patented Dec. 11, 1906.

Application filed May 20, 1904. Serial No. 208,835.

To all whom it may concern:

Be it known that I, CARL WEIDMANN, engineer and assistant in the Royal Polytechnic at Aix-la-Chapelle, a subject of the 5 King of Prussia, German Emperor, residing at Grevenberg, near Aix-la-Chapelle, in the Kingdom of Prussia, Empire of Germany, have invented certain new and useful Improvements in Combustion-Engines; and I 10 do hereby declare the following to be a full, clear, and exact description of the invention, such as will enable others skilled in the art to which it appertains to make and use the same.

15 My present invention relates to combustion-engines, and particularly to the means for compressing the combustibles to a far higher degree than hitherto it has been possible to do in order to obtain a higher thermal efficiency of the engine. To do this rationally, the combustibles must be compressed in a manner to prevent their premature ignition by means of the heat generated during the act of compression. At all events 20 the combustibles must be compressed in a separate pump, as the cooling of the combustibles within the working cylinder itself cannot be done thoroughly enough, as in said cylinder they cannot be sufficiently influenced by the cooling medium.

It is well known that in combustion-engines wherein the compression of the combustibles, as well as the compression of the air, takes place separately great difficulties 35 are encountered in transferring the compressed combustibles to the working cylinder after compression has taken place, as practically it is impossible to always create within the compression-chamber of the pump the exact pressure required for the correct overflow.

In the combustion-engine described below the air is compressed in the working cylinder, whereas the combustibles are compressed in 45 a separate pump, with the especial view that the air and the combustibles show approximately the same pressure. Besides this a very intensive compression can be obtained by arranging an exceptionally well cooled 50 chamber, destined for the reception of the combustibles, in a similar manner as in receiver-engines, thus obtaining not only a high compression, but also excluding the possibility of a premature ignition taking place.

55 This engine further offers the means for

obtaining a compulsorily-regulated combustion—*i. e.*, the combustion of the combustibles depends entirely on compulsorily-actuated parts of the engine, whereas in explosive-engines the combustion of the whole of the combustibles is left to its own devices after they have been brought to ignition, which in such engines takes place at one point. On account of the equal pressures of the air and 60 the combustibles obtained by the aid of this mode of regulation the combustibles necessary for the combustion need not be pressed into the working cylinder against the pressure existing in the latter, but simply need to be 65 pushed from one compression-chamber to another—*i. e.*, from the chamber containing the combustibles to the combustion-chamber of the working cylinder—which transfer can be executed without any difficulties whatever, as in both chambers the same pressure 70 exists.

In the accompanying drawings, Figure 1 is a vertical longitudinal sectional view of the combustion-engine, and Fig. 2 is an end 75 view of the same. Fig. 3 is a cross-sectional view on the line 3 3 of Fig. 1. Fig. 4 is a similar view on the line 4 4 of Fig. 1. Fig. 5 is another cross-sectional view on the line 5 5 of Fig. 1. Figs. 6, 7, 8, and 9 are diagrams 80 showing the relative positions of the cranks and the cam employed for operating the several pistons at the different stages of the work.

The crank-shaft 1 is suitably journaled in 85 a well-known manner in the base 2 of the combustion-engine, upon which the frame 3 thereof is secured. This frame 3 contains the working cylinder 4 and the pump-cylinder 5. Within the cylinder 4 plays the piston 6, connected with the crank 7 of the crank-shaft 1 by means of the connecting-rod 8, whose upper end may be connected in any suitable manner to pin 9 of the piston 6. In a similar manner the piston 10, playing in the cylinder 5, is connected with the crank 11 of the crank-shaft 1 by means of the connecting-rod 12, whose upper end is connected with the piston 10 by means of the pin 13, seated in said piston 10. The crank 11 is about twenty to thirty degrees in advance of the crank 7.

To the left of the base 2 a helical wheel 14 is seated upon the crank-shaft 1 and meshes with a similar wheel 15, keyed to the vertical 110 shaft 16, which is held to the base of the engine and to the working cylinder 4 by means

of the brackets 17 and 18, respectively. Above the bracket 18 another helical wheel 19 is keyed to the shaft 16 and meshes with a similar wheel 20, seated upon a cam-shaft 21, 5 running parallel to the crank-shaft 1 and making the same number of revolutions per minute as the crank-shaft 1. The cam-shaft 21 is journaled in the brackets 22 and 23, of which the former is secured to the cylinder 10 and the latter to the cylinder 5. (See Figs. 2 and 4.)

When the piston 6 has nearly finished its downstroke, it uncovers the exhaust-ports 24, through which the residue of the products of combustion of the previous combustion can escape into the annular casing 25, whence they may be led to any desirable point by means of the pipe 26.

In the cover 27 of the cylinder 4 is seated 20 an air-valve 28, whose stem 29 is attached to the one end of the lever 30 pivoted in the bracket 31, which is secured to the cylinder-cover 27. With the other end of the lever 30 is connected a rod 32, whose lower end is 25 held in position by an arm 33, pivotally attached to the side of the cylinder 4. The air-valve 28 is kept on its seat by means of the spring 34, placed between the arm 33 and the bracket 35, secured to the side of the cylinder 4. The lower end of the rod 32 is provided with a friction-roller 36, contacting with a cam 37, secured to the cam-shaft 21. To the cylinder-cover 27 is fastened a pipe 38, connected with a blower (not shown) 30 furnishing air under a slightly higher than atmospheric pressure. Fig. 3 shows the air-valve 28 partly opened, so that the slightly-compressed air from the blower can enter the working cylinder 4 and blow 35 the last traces of the products of the previous combustion through the exhaust-ports 24 into the annular casing 25.

In the cover 39 of the pump-cylinder 5 is seated a suction-valve 40 and is kept to its seat by the spring 41, surrounding the valve-stem 42, to which is pivotally attached the one end of the lever 43. This lever is pivoted in the bracket 44, attached to the cover 39, and its free end connected with a rod 45, 45 carrying in its lower end a friction-roller 46. In order to prevent the lower end of the rod 45 from leaving the cam 47, an arm 48 is pivotally connected with the bracket 49 on the cylinder 5. (See Fig. 4.) As may be seen in the last-named figure, the valve 40 is kept open until the piston 10 has reached its lower dead-point, so that gas can freely enter the cylinder 5 through the pipe 50. As the piston 10 commences its upstroke 50 earlier than the piston 6 on account of the crank 11 being in advance of the crank 7, it follows that it must finish its upstroke, too, earlier than the piston 6 does. To prevent the compression of the gas in the pump-cylinder 5 commencing earlier than the comp-

ression of the air in the working cylinder 4, the suction-valve 40 is kept open by means of the cam 47. In doing so a part of the gas drawn into the cylinder 5 during the down-stroke of the piston 10 will return into the pipe 50 at the beginning of the upstroke of the piston 10. This escape of the gas into said pipe, in fact, continues until the piston 6 covers the exhaust-ports 24 on its up-stroke. As soon as the exhaust-ports are 75 shut off by the piston 6 the air-valve 28 and the suction-valve 40 are shut off simultaneously, so that the compression of the gas, as well as of the air, begins at the same moment. 80

Between the working cylinder 4 and the pump-cylinder 5 a chamber 51 for the reception of the compressed combustibles is arranged, which chamber has the shape of a flat pipe and is provided with a cooling-jacket 52, 85 into which the cooling medium enters through the pipe 53 and leaves it on the opposite end through the pipe 54. These pipes may be provided with any suitable means to regulate the flow of the cooling medium through 90 the cooling-jacket 52. The end 55 of the chamber 51 is provided with an automatic check-valve 56, opening into the chamber 51, whereas the other end 57 is attached to a displacer-cylinder 58, communicating with the 95 interior of the cylinder 4 by means of the port 59, which is made wide enough to leave a narrow opening above and below the displacer-piston 60 when the latter takes up its lowest position. By this arrangement the displacer-piston 60 is balanced to a high degree, for which reason it can be easily started and moved. The free end of the piston-rod 61 is connected with a lever 62, pivotally secured to the bracket 63, carried by the cylinder 4. 100 The free end of the lever 62 is provided with a friction-roller 64, running in a groove 65 of the cam-disk 66, seated upon the cam-shaft 21, so that the motion of the displacer-piston 60 is always under the control of the grooved 110 cam-disk 66.

The working cylinder 4 is also connected with the end 55 of the chamber 51 by means of the valve 67, whose stem 68 is surrounded by a spring 69, placed between the boss 70 of the cylinder 4 and the one end of the lever 71 which is pivotally secured to the cylinder 4 by means of the bracket 72. The other end of the lever 71 carries a friction-roller 73, which is kept in contact with the cam 74, 115 seated upon the cam-shaft 21. The valve 67 is always closed during the time compression takes place in the cylinders 4 and 5.

During the compression of the gas the latter enters the chamber 51 by raising the 120 check-valve 56, because the compression in the cylinder 5 has a tendency to advance quicker than the compression in the working cylinder 4, as there exists a far smaller clearance-space in the cylinder 5 than in the cylinder 130

der 4. For this reason the compressed gas will advance in the chamber 51 to a point lying nearer to the end 57 than to the end 55 thereof, and thereby force back the air contained therein. As soon as the piston 10 has reached its upper dead-point, which on account of the advance of the crank 11 to the crank 7 takes place earlier in the pump-cylinder 5 than in the working cylinder 4, the check-valve 56 returns to its seat, as no more gas is present to keep it open. As after the closing of the check-valve 56 the piston 6 is still advancing, the contents of the cylinder 4, of the cylinder 58, and of the chamber 51 are still further compressed, during which period of compression the gas contained in the chamber 51 will be moved toward the end 55 of the latter by means of the compressed air pressed into the other end of the chamber 51 by the piston 6.

As soon as the piston 6 reaches its upper dead-point the relief-valve 67 will be lifted off its seat by means of the cam 74. Simultaneously therewith the displacer-piston 60 will be raised by means of the cam-disk 66, whereby the displacer-piston 60 will close the port 59 while moving upward, thus severing the connection between the cylinder 4 and the end 57 of the chamber 51, and simultaneously therewith the contents of the displacer-cylinder 58 and those of the chamber 51 are pushed toward the cylinder 4, serving here as combustion-chamber. It is evident that in doing so the contents of the chamber 51 lying next to the valve 67 will enter the cylinder 4 first and fill the space between the piston 6 and the cylinder-cover 27, and as this part of the contents of the chamber 51 is composed of gas the latter can after entering the cylinder 4 and mixing with the air contained therein be ignited in any desirable or known manner, so that the gas will be burned upon entering the working cylinder 4. During the time combustion takes place the piston 6 pursues its downstroke, and to prevent an undue increase or decrease of pressure the displacer piston 60 must move with a speed bearing a certain ratio to the speed of the working piston 6 while pushing the gas into the working cylinder 4.

After all the gas has been burned the expansion of the products of combustion contained in the cylinder 4 begins and continues while the piston 6 moves downward. Simultaneously therewith the piston 10 is on its downstroke and draws the necessary quantity of gas for the next charge into the cylinder 5. During the downstroke of the piston 6 the displacer-piston 60, too, begins its downstroke after it has pushed all the combustibles into the combustion-chamber, which in this instance is the cylinder 4 itself. The valve 67 is now closed too. As soon as the piston 6 has passed the exhaust-ports 24 the

cycle of operations described above can re- 65 commence.

To show at a glance the relative positions of the three pistons 6, 10, and 60 during the different stages of the work, the crank-diagrams (shown in Figs. 6, 7, 8, and 9) have 70 been added, in which each piston is represented by its crank or cam, a method usually employed to ascertain the movement of a piston corresponding to a given angular motion of the crank driving it. To simplify 75 matters, the parts used in the diagrams are designated by the same numbers as the parts of the drawings they represent. It will be noticed that the cam-disk 66 is shown in these figures as being seated upon the shaft 80 1. This does not, however, influence the correctness of the following statements, as the cam-shaft 21 and the crank-shaft 1 not only make the same number of revolutions per minute, but also rotate in the same direction. 85

Commencing with Fig. 6, it will be seen that the crank 11, as well as the crank 7, moves upward, while the friction-roller 64 rests upon the highest part of the cam-disk 66. Consequently the pistons 10 and 6 are on their upstroke while the displacer-piston is at rest in its lowest position, for which reason the port 59 is open, the valves 28, 40, and 67 are closed, and the compression in the cylinders 90 4 and 5 takes place, whereby the check-valve 56 is kept open, so that the compressed gas can enter into the chamber 51, while the compressed air enters into the chamber 51 by way of the port 59 and displacer-cyl- 95 100 nder 58.

In Fig. 7 the crank 11 has reached its upper dead-point while the crank 7 still ascends and the lever 62 remains in the same position as shown in Fig. 6, which facts show that the 105 piston 10 has reached its upper dead-point while the piston 6 is still on its upstroke and the piston 60 remains in the position shown in Fig. 1. After the piston 10 has completed its upstroke the check-valve 56 must close 110 and the pressure in the chamber 51 must rise, since the piston 6 still compresses the air in the cylinder 4 and presses it through the port 59 into the end 57 of the chamber 51. The valve 67 is still closed. 115

Fig. 8 shows that the piston 10 is on its downstroke while the piston 6 has reached the upper dead-point and is ready to begin its downstroke. The displacer-piston now begins to ascend and to close the port 59. 120 Corresponding to these positions of the pistons 6 and 60 the valve 67 is now opened and the piston 60 presses the combustibles into the working cylinder 4 to burn there upon entering, after which expansion takes place. 125 The piston 10 descends, and thereby draws a new volume of gas into the cylinder 5 through the valve 40 for the next charge.

When the cranks 11 and 7 and the cam 66 are in the positions shown in Fig. 9, the piston 10 has almost reached its lower dead-point and the piston 6 just uncovers the exhaust-ports 24. The air-valve 28 is opened, so that all traces of the last combustion can be removed, and fresh air may be drawn into the cylinder 4. The position of the lever 62 shows that the displacer-piston 60 begins to descend, and as soon as it has reached its lowest position the valve 67 is closed, and the compression in both cylinders can commence anew as soon as the exhaust-ports 24 and the valves 28 and 40 have been closed.

To fully understand the nature of this invention, a clear conception of the conditions must be obtained which have to be fulfilled in order to have the engine work as outlined above. When the crank 11 is in advance of the crank 7, the kind of condition is created which exists in a compound engine with an intermediate receiver—*i. e.*, the pump-piston 10 does not compress the gas up to the highest degree of pressure, as this is done by the working piston 6 only. This compression of the gas to the highest degree of pressure takes place in a chamber 51, which can be easily so shaped that a thorough cooling of the gas is made possible, whereas a perfect and thorough cooling of the gas when enclosed in a cylinder is an absolute impossibility. In order to cool the gas most energetically and to prevent the gas in the chamber 51 from mixing the air likewise contained in this chamber and being pushed back therein by the gas, this chamber must have the shape of a pipe, and preferably the shape of a flat pipe or, if necessary, a number of smaller pipes may be employed whose area is at least equal to the cross-sectional area of a pipe-like chamber sufficiently large for the work in hand. From the foregoing it will be seen that the engine can only work as it should when during the period of compression the gas in the chamber 51 is not pushed far enough toward the end 57 of the latter so as to enter the displacer-cylinder 58, as in this comparatively large cylinder the gas cannot be sufficiently cooled, and besides this the gas could not, if once entered into the displacer-cylinder 58, be returned completely and in a uniform stream into the working cylinder 4 by way of the cooled chamber 51, so that a compulsorily-regulated combustion would become an impossibility.

The only means to prevent the gas from being shifted during the period of compression from the cooled chamber 51 into the displacer-cylinder 58 is to make the angular advance of the crank 11 in regard to the crank 7 sufficiently small, as all the other factors—as, for instance, the cubical contents of the different chambers and cylinders—are fixed by the required mechanical effect of the engine, by the heating power of the gas, and

by the desired maximal pressure, which factors cannot be changed at will.

The arrangement of a cooled pipe-like chamber 51, as shown and described, does not alone suffice to make the engine work as its nature requires. It rather becomes a necessity that in combination with this pipe-like chamber 51 the angle of advance between the crank 11 of the pump-piston 10 and the crank 7 of the working piston 6 is not made so large that during the period of compression the gas is pressed from the chamber 51 into the displacer-cylinder 58.

I am fully aware of the fact that in putting my invention into practice the shape and arrangement of the parts employed may be altered in various ways—as, for instance, the port 59 might be opened and closed by means of a slide or by a valve and the cooled chamber 51, which here consists of a flat pipe, might be replaced by a number of smaller pipes either cast in one piece or by a number of separate pipes. Besides this many other possible changes might be mentioned; but all these would not in the least alter anything in the nature of my combustion-engine and its correct working, and therefore fall within the scope of my invention, for which reason I wish it to be understood that I do not desire to bind myself to the exact construction and arrangement of parts shown here.

I claim—

1. In a combustion-engine the combination with a pump-cylinder and a working cylinder of a cooled pipe-like chamber for the reception of the compressed combustible communicating alternately at the one end with said working cylinder and at the other end at one time with said pump-cylinder and at another time with said working cylinder; means for establishing a communication between said pump-cylinder and said cooled pipe-like chamber during the time the combustible is introduced into said cooled pipe-like chamber; means for closing said communication after said combustible has been introduced into said pipe-like chamber; means for establishing a communication between the working cylinder and said cooled pipe-like chamber at the end of the latter lying opposite the end of said chamber provided with the entrance-opening for the combustible, during the time the compression is taking place; means for closing this communication after the compression is completed; means for establishing a communication between said working cylinder and said cooled pipe-like chamber at the end of the latter where the combustible is entering it; means for pushing the combustible after the compression out of said pipe-like chamber into said working cylinder in the opposite direction it entered said cooled pipe-like chamber.

2. In a combustion-engine the combina-

tion with a pump-cylinder and a working cylinder of a cooled pipe-like chamber for the reception of the compressed combustible communicating alternately at the one end with said working cylinder and at the other end at one time with said pump-cylinder and at another time with said working cylinder; a relief-valve to open into said cooled pipe-like chamber while the combustible is entering the latter and to close when the combustible has entered said pipe-like chamber; a displacer-piston situated at the end of said cooled pipe-like chamber lying opposite the one where said relief-valve is arranged and capable of establishing a communication between said working cylinder and said pipe-like chamber when in one end position and pushing the compressed combustible into the working cylinder while moving into its other end position after having closed the communication with the working cylinder; and a mechanically-operated valve for admitting the compressed combustible into said working cylinder when the combustible is pushed by said displacer-piston and arranged at the end of said cooled pipe-like chamber where said relief-valve is situated.

3. A combustion-engine comprising in combination a working cylinder; a pump-cylinder; a cooled pipe-like chamber for the reception of the compressed combustible communicating alternately at the one end with said working cylinder and at the other end at one time with said pump-cylinder and at another time with said working cylinder; a cooling-

jacket surrounding said pipe-like chamber; a combustible-inlet valve for admitting the combustible to said pump-cylinder; a relief-valve admitting the compressed combustible to said cooled pipe-like chamber; a displacer-piston admitting the compressed air to said cooled pipe-like chamber when in one end position and pushing the compressed combustible into said working cylinder while moving into its other end position; in the opposite direction it entered said cooled pipe-like chamber; means for operating said displacer-piston; a mechanically-operated valve for admitting the compressed combustible to the working cylinder; means for operating the last-named valve; exhaust-ports arranged in the walls of said working cylinder; an annular casing covering said exhaust-ports on the outside of said working cylinder to receive the residue of combustion and lead it to an outlet-pipe; a valve for admitting air to the working cylinder; means for operating the air-inlet valve; means to keep open the combustible-inlet valve until said working piston has covered said exhaust-ports on its upstroke; means for operating said working piston; and means for operating said pump-piston.

In testimony whereof I have signed my name to this specification in the presence of two subscribing witnesses.

CARL WEIDMANN.
